UNITED STATES PATENT OFFICE.

XAVIER B. KONKEL, OF DETROIT, MICHIGAN.

CANDELABRUM.

SPECIFICATION forming part of Letters Patent No. 742,039, dated October 20, 1903.

Application filed July 16, 1902, Serial No. 115,775. (No model.)

To all whom it may concern:

Be it known that I, XAVIER B. KONKEL, a citizen of the United States, residing at Detroit, county of Wayne, State of Michigan, have invented certain new and useful Improvements in Candelabra; and I declare the following to be a full, clear, and exact description of the invention, such as will enable others skilled in the art to which it pertains to make and use the same, reference being had to the accompanying drawings, which form a part of this specification.

My invention relates to an improved candelabrum, and especially to that class commonly employed at funerals; and its object is to produce one that will fold up, so that it may be reduced in compass for carrying, compactness in storing, and in packing for transportation; and it consists in the novel features and combinations hereinafter described and claimed.

In the drawings, Figure 1 is a side elevation showing the device when erected for use. Fig. 2 shows it when folded for transportation. Fig. 3 illustrates the manner of folding the cross, shown upright in Fig. 1 and folded in Fig. 2. Fig. 4 is a cross-section on lines *xx* of Fig. 1.

Similar figures refer to similar features.

As usually constructed the candelabrum has a foot or base, a central upright stem, and one or more tiers or branches adapted to hold lights. The base is usually formed in the shape of a tripod, and for clearness only two of the branches are shown forming the base instead of three, so that there may be more than two branches or tiers of branches; but for clearness I have only shown two opposite branches and two of the tiers of branches above the same.

In the drawings, 1 1 are the lower foot-stems of the tripod. These are pivoted to a basic closed ferrule or support 2 in such manner that they not only will fold downward, as shown in Fig. 1, but outwardly, as shown in Fig. 2. From the ferrule a stem 3 rises and is rigidly attached thereto. This stem is formed with three or more flutes or grooves, as shown at 4 4 in Fig. 4. Surrounding the stem 3 is a collar 5, and this carries one or more set-screws 6. These set-screws are adapted to engage in the grooves 4 4 of the

stem 3. To this collar are pivoted arms 7 7, which are also pivoted at 8 8 to the arms 1 1 of the tripod. Obviously if the collar 5 be slid up along the stem 3 by virtue of the links or connections 7 7 it will draw the arms 1 1 upwardly into position shown in Fig. 2. The fluted tube 3 carries a secondary tube 9, which telescopes within it, and this in turn encircles a third tube or bar 10, which also telescopes in 9, passing through ferrule 11, rigidly attached to the tube 9, and having wings or cheek-pieces for pivots 12 12. To these are pivoted, so that they can swing upwardly or downwardly, arms 13 13. The upper end of the tube or rod 10 carries a fitting 14, to which are pivoted arms 15 15. To these arms are also pivoted at 16 16 the arms or braces 13 13. On the opposite side of arms 15 15 are also pivots 17 17, to which are pivoted another set of arms or braces 18 18. The opposite ends of these arms 18 18 are pivoted to a common fitting 19, and to this is also pivoted at 31 by the construction shown in Fig. 3 a cross and other insignia 20, this latter pivot 31 being such as to enable the cross to fold downwardly, and thus shorten the length of the whole structure as shown in Fig. 2. The arms 15 and 18 carry proper supports for candles 21 21, (as many of them as may be desired.)

In use the operation of this combination is as follows: If we assume the structure as erected in Fig. 1, the fitting or sleeve 5 would be raised along the tube 3 to a position shown in Fig. 2. This would fold up the bottom or tripod, so that the arms assume the position shown in Fig. 2. The arms 15 15 would fold downwardly, raising the fitting 14 and its depending tube 10, which is affixed thereto, thus folding the arms 15 15 and the links 13 13 down closely together. At the same time it draws down the fitting 19 by virtue of the arms 18 18, which are pivoted at 17 17 to the arms or braces 15 15, whereby the upper portion carrying the cross is drawn down approximately and nearly to the fitting 14. The cross 20 is then folded down in close proximity to the arms which have previously been folded. When it is desired to use the device, the tripod-arms 1 1 are extended by slipping the fitting 5 down along the tube 3, and when the desired spread of the arms is attained the

set-screw 6 is used to firmly fix the fitting 5 to the tube 3. I flute the tube 3, as shown at 4 4 in Fig. 4, so that the impingement of the set-screws thereon shall not mar the tube, as 5 their points engage in the groove formed. I have shown three grooves and correspondingly there might be three set-screws. A similar set-screw 22 is furnished in a collar 25 at the top of tube 3, so that the tube 9 can 10 be held rigidly with reference to the tube 3. A similar set-screw 24 impinges through the fitting 11 upon the rod 9, whereby the rod 10 can be held in any fixed position along said rod 9. The set-screws 22 are released, the 15 tube 10 drawn outwardly in the tube 9, thus spreading the arms 15 15 by virtue of the links 13 13, and at the same time raising fitting 19 through the pivotal arms 18 18 until the desired angle and elevation is attained. 20 Then the set-screws 22 and 24 fix the parts in position upward, the cross 25 can be erected into the position shown in Fig. 1.

It is evident that the pattern may be made as plain or ornamental as may be desired. It 25 is also evident that the pivots or hinges may be made in any convenient form and may be ornamented, if desired. As these are not the essence of my invention and well known in the art of hinging, I do not deem it necessary 30 to describe them in detail. The candelabrum can have also any desired proportions.

Having thus described my invention, what I desire to claim is—

1. A candelabrum having hinged, folded 35 branches, each provided with a candle-holder, a secondary tier of branches supported by the first and hinged thereto, said second tier of

branches supported by pivotal attachment, a cross or other insignia having a pivoted or hinged connection to the upper tier of 40 branches, the whole adapted to fold downward and thus shorten the length, substantially as described.

2. The combination to form a candelabrum, of a base or foot formed of a reversible, 45 collapsible tripod, having branches engaging a sliding fitting, and means for securing said fitting in any desired position, a tube carried by said tripod, said tube carrying telescopic- 50 ally a second tube and stem, said tube and stem carrying arms supported by braces, said arms and braces being pivoted and adapted to fold downward simultaneously with the extending of the said second tube, substantially as described.

3. In a candelabrum, the combination of arms pivoted to a supporting means whereby said arms are caused to rise or fall from an approximate parallel to an approximate transverse position to said stem, a secondary set of 60 arms carried by the first set, supports thereon for candles, said secondary set of arms carrying a fitting adapted to support a cross or other insignia having a pivoted or hinged connection to the upper tier of branches to 65 enable them to be folded, substantially as described.

In testimony whereof I sign this specification in the presence of two witnesses.

XAVIER B. KONKEL.
